(57) **CLAIM**

The ornamental design for a dispenser for dispensing a fluid into a nasal cavity, as shown and described.

DESCRIPTION

FIG. 1 is a perspective view from above of one side and one end of the dispenser for dispensing a fluid into a nasal cavity showing our new design;

FIG. 2 is a perspective view from below of one side and one end thereof;

FIG. 3 is a side view thereof;

FIG. 4 is an end view thereof;

FIG. 5 is an opposite end view thereof;

FIG. 6 is an opposite side view thereof;

FIG. 7 is a plan view thereof; and,

FIG. 8 is an underneath plan view thereof.
